Primary Examiner — Richard A Edgar*Assistant Examiner* — Jessica Ruth Grable(74) *Attorney, Agent, or Firm* — Carter, DeLuca & Farrell, LLP(57) **CLAIM**

The ornamental design for an activity tray, as shown and described.

DESCRIPTION

FIG. 1 is a front, right, top perspective view of an activity tray, in accordance with the present design, illustrating an electronic device/tablet (shown in phantom) supported thereon;

FIG. 2 is a rear, left, top perspective view of the activity tray, of FIG. 1;

FIG. 3 is a left, side elevational view of the activity tray of FIGS. 1 and 2; and,

FIG. 4 is a top, plan view of the activity tray of FIGS. 1-3. The broken lines in the drawings depict portions of the activity tray that form no part of the claimed design. The dash dot dot broken lines are for the purpose of disclosing environment that form no part of the claimed design.

1 Claim, 4 Drawing Sheets(56)
